UNITED STATES PATENT OFFICE.

JOSEPH SLEPIAN, OF SWISSVALE, PENNSYLVANIA, ASSIGNOR TO WESTINGHOUSE ELECTRIC & MANUFACTURING COMPANY, A CORPORATION OF PENNSYLVANIA.

STATIC-REDUCING SYSTEM.

Application filed October 20, 1921. Serial No. 509,166.

My invention relates to protective systems and more especially to apparatus and circuit arrangements adapted to minimize the disturbing effects of static impulses in wire-
5 less receiving systems.

An object of my invention is to provide an improved receiving system embodying means whereby the disturbing effects of atmospheric electricity or static disturbances
10 may be simply and efficiently eliminated.

It is found that many static disturbances in a wireless receiving system consist of a brief impulsive blow to the antenna system during which time energy is stored in the
15 antenna, and this energy immediately afterwards manifests itself by an oscillation having the natural period and the damping of the antenna system. The distinction, therefore, between such disturbances and received
20 signal impulses is that the energy is stored in the antenna only in the first impulse of short duration.

According to my invention, I provide means adapted for use in connection with
25 well known types of receiving systems, whereby the energy in the initial impulse of the static disturbance may be absorbed in an impedance device, thereby preventing the static impulse from storing energy in the
30 antenna in the form of natural oscillations and, as a result, producing substantially no effect upon the receiving system. In carrying out this feature of my invention, I select an absorbing impedance that will absorb but
35 little energy of the signaling frequency although effectively damping the impulses due to static disturbances.

The desired result may be accomplished by including in the receiving circuit a pair
40 of high-impedance, inductive-reactance devices and shunting each device by a rectifier, the several rectifiers being oppositely directed.

Other objects and applications of my invention, as well as details of construction, whereby my invention may be practiced, will be apparent in the following description and claims when read in connection with the accompanying drawing, wherein
45 The single figure is a diagrammatic view of a wireless receiving system embodying my invention.

In the single figure an antenna 1 is con-

nected to a ground conductor 2 through a tuning coil 3 and a pair of serially connected high-impedance, inductive-reactance devices 4 and 5. The inductance-reactance device 4 is shunted by an asymmetrical conducting device or rectifier 6 while the inductive-reactance device 5 is shunted by a similar asymmetrical conducting device or rectifier 7, the two rectifiers, however, being oppositely directed. The combined impedance of the devices 4 and 5 is great enough if the shunts 6 and 7 were omitted to render the antenna circuit aperiodic.

Wave responsive apparatus (not shown) may be operatively connected to the antenna circuit through conductors 8, 9 and a coupling coil 11, the latter member being operatively associated with the tuning coil 3.

In operation, upon the receipt of signal impulses, the effect of successive positive half-cycles is to cause unidirectional currents to progressively build up in a circuit
75 12 which includes the reactance device 4 and the rectifier 6. The direction of the currents is as indicated by arrow *a* in the drawing. The final value of the currents is that of the peak value of the currents in the antenna
80 circuit.

Similarly, the effect of the successive negative half-cycles is to cause similar unidirectional currents to traverse a circuit 13, the latter including the reactance device 5 and the rectifier 7. It will be noted, however, that the currents in this circuit are in a reverse direction to those in circuit 12, as indicated by arrow *b*. Here again, the final value of the currents is that of the peak
85 value of the alternating currents in the antenna circuit.

Since the effect of the positive and the negative half-cycles of the received impulses is to cause unidirectional currents of value *i* corresponding to the peak values of the received impulses to traverse the several rectifiers, it is seen that the positive and the negative half cycles of the received impulses are readily by-passed around the impedance devices 4 and 5 through the rectifiers 6 and 7, respectively. The currents through the rectifiers 6 and 7 are thus oppositely varied between zero and twice the normal unidirectional-current value.

Upon the receipt of the disturbing im-

pulses, however, having potentials greater than the peak potentials of the received signal impulses, positive half cycles are blocked by the rectifier 6, and, similarly, negative half cycles are blocked by the rectifier 7, with the result that the total energy of the disturbing impulse is absorbed in inductance coils 4 and 5. The energy which is thus absorbed in the inductance coils is dissipated in the resistance of the closed circuits 12 and 13.

In view of the foregoing description, it can be readily seen that, for signaling impulses, the rectifiers serve as low-impedance paths around the several impedance devices but that, for disturbing impulses having steep wave-fronts, and potentials above the peak of the signal current potentials as are found in static impulses, the rectifiers serve as high-impedance paths tending to admit of the inductive devices 4 and 5 rapidly damping out the disturbing impulses.

While I have described certain characteristic forms of my invention in detail, and while I have pointed out certain of the most obvious principles and purposes thereof, I do not intend the language employed in the following claims to be limited to the precise features described, but I intend that the claims shall be construed to cover all combinations which are fairly included in the language thereof, when made in connection with the prior art, regardless of the details and functions mentioned in the description or illustrated in the drawing.

I claim as my invention:

1. In an electrical system, a circuit carrying oscillatory currents, a high-impedance device included in said circuit and means for rendering said impedance device substantially non-effective for said currents, said means being effective for sustained signaling waves independent of the amplitude thereof and substantially ineffective for current impulses of brief duration.

2. In a wireless receiving system, an antenna circuit for receiving signal impulses, a high-impedance device tending to damp out said signal impulses and means for rendering said impedance device substantially ineffective for said signal impulses, said means being effective for sustained signaling waves independent of the amplitude thereof and substantially ineffective for disturbing impulses of very brief duration.

3. In an electric system, a circuit including resonant capacitive and inductive-reactance devices, a reactive impedance element included in said circuit for rendering said circuit aperiodic and means for rendering said reactive impedance element ineffective for current corresponding to the natural frequency of said resonance, said means be-

ing independent of the amplitude of said current and leaving said impedance device effective for disturbing impulses of brief duration, said means comprising a pair of oppositely asymmetrical conducting paths each in shunt to a different portion of said impedance element.

4. In a wireless receiving system, a receiving conductor, a pair of high-impedance devices included in circuit therewith, the impedance of said devices being such as to damp out static as well as signal impulses, and means shunting each device for rendering said devices ineffective for currents having predetermined characteristics, said means being independent of the amplitude of said currents and substantially ineffective for steep wave-front surges impressed upon said conductor.

5. In a wireless receiving system, a receiving conductor, a pair of high-impedance, inductive-reactance devices serially included in circuit therewith, the impedance of said devices being such as to render said conductor non-oscillatory, and an asymmetrically conducting path shunted around each device, said path being oppositely directed, whereby said impedance devices may be rendered ineffective for received signal impulses, said paths being ineffective, respectively, for steep wave-front surges of opposite potential, the effectiveness of said paths being independent of the current strength.

6. In a wireless receiving system, a receiving conductor, means included in circuit therewith for damping out static impulses and a low-impedance path around said first-mentioned means, said path including means cooperating with said first-named means to determine a critical potential dependent upon the magnitude of the steady received signal impulses and for rendering the path ineffective above said critical potential.

7. In a wireless receiving system, a receiving conductor, an inductive impedance device serially included in circuit therewith for rendering said conductor non-oscillatory and a pair of low-impedance paths around said first-mentioned inductive impedance, said paths each including means cooperating with said inductive impedance, to determine a critical potential dependent upon the magnitude of the steady received signal impulses and for rendering the path ineffective above said critical potential and said means being oppositely connected in the respective paths.

8. In a wireless receiving system, a receiving conductor carrying currents having positive and negative half cycles, a pair of inductive-reactance devices serially included in circuit therewith, a path shunting each device, an asymmetric resistor in each path,

said resistors being oppositely connected and each constituting approximately all the resistance in the respective paths.

9. In combination with a receiving circuit, means for preventing response therein to impulsive energy while permitting response to signaling energy, said means including a network presenting large and approximately constant impedance to impulsive energy and low impedance to signaling energy.

10. The combination with an alternating-current circuit to be protected from currents having an abnormally steep wave-front, of protective means including reactance means connected in series with said circuit and auxiliary means for rendering said reactance means substantially ineffective to impede the desired alternating currents in the circuit, said auxiliary means being substantially ineffective for all currents having an abnormally steep wave-front and exceeding the amplitude of the said desired alternating currents.

11. The combination with an alternating-current circuit to be protected from currents having an abnormally steep wave-front, of protective means including a pair of series-connected inductors in said circuit and a shunt path for each inductor, each path including a device cooperating with the respective inductors for causing a circulating unidirectional component of current having a value proportional to the average maximum value of the alternating current in the alternating-current circuit, said circulating unidirectional currents in the respective inductors being in opposite directions, the current-carrying power of said devices being sufficient for the maximum expected currents.

12. The combination with an alternating-current circuit subject to current changes having a relatively small value per cycle and also subjected to current changes having a relatively large value per cycle, of protective means including a pair of series-connected inductors in said circuit and means connected in shunt to the respective inductors for effecting the establishment of circulating unidirectional components of current having a value within the limits of substantially said small value, said means having a current-carrying capacity sufficient for said current changes of relatively large value and said circulating unidirectional currents in the respective inductors being in opposite directions.

13. In an electrical system, a circuit adapted to be energized from a desired source of alternating currents and also from an undesired source of currents having relatively steep wave-fronts, impedance

means included in said circuit and auxiliary means energized from said impedance means and thus carrying currents proportional to the average current in said circuit for rendering said impedance means relatively non-effective for said desired currents and effective for said undesired currents, said auxiliary means being capable of carrying currents of any strength up to a magnitude that would injure the apparatus.

14. The combination with an alternating-current circuit to be protected from currents having an abnormally steep wave-front, of protective means including a pair of multiple paths serially connected in said circuit, each of said multiple paths comprising a main path carrying currents substantially constant during the absence of said currents having abnormally steep wave-front and an auxiliary path carrying currents varying during said absence between the limits of substantially zero and substantially twice the currents in said main path, the currents in the main paths of said pair of multiple paths being substantially equal and opposite in direction, and means for maintaining the stated current-flows in the several paths, said auxiliary paths having a current carrying capacity sufficient for the maximum currents expected in said circuit to be protected.

15. The combination with an alternating-current circuit to be protected from currents having an abnormally steep wave-front, of protective means including a pair of serially-connected inductors connected in series with said circuit and a pair of asymmetrically conductive circuits, capable of carrying currents corresponding to the maximum expected amplitude of said abnormally steep wave-fronts, connected in opposite directions in shunt, respectively, to said inductors.

16. In a protection device, an inductor, and a pair of asymmetrical resistance devices, one of said asymmetrical devices being connected in shunt to said inductor, and the other affording a passage for current through said inductor, whereby, when alternating current is impressed upon the protection device, the average current through said shunt will approximate the maximum current through said inductor, the conductivity of said passage being independent of the current strength.

17. In a protection device, a pair of inductors connected in series and a pair of asymmetrically conducting devices, one in shunt to each inductor, the conductive direction of said devices being away from the point where said inductors are connected to each other.

18. In a disturbance-eliminating device, an inductance divided into two parts, two

shunts, one about each of said parts, and asymmetrically resistive devices, one in each of said shunts, and means for supplying a varying current to said inductance, the common connection from the division point of said inductance to the adjacent ends of said asymmetrically resistive devices maintain-

ing said three points at one potential.

In testimony whereof, I have hereunto subscribed my name this 30th day of Sep- 10
tember, 1921.

JOSEPH SLEPIAN.
